(57) **CLAIM**

The ornamental design for a pie, as shown and described.

DESCRIPTION

FIG. 1 is a perspective view of a first embodiment of a pie showing my new design;

FIG. 2 is a top plan view thereof;

FIG. 3 is a left side elevation view thereof;

FIG. 4 is a perspective view of a second embodiment of a pie;

FIG. 5 is a top plan view thereof;

FIG. 6 is a perspective view of a third embodiment of a pie;

FIG. 7 is a top plan view thereof;

FIG. 8 is a perspective view of a fourth embodiment of a pie; and,

FIG. 9 is a top plan view thereof.

The broken lines shown in FIGS. 1–9 illustrate portions of the pie that form no part of the claimed design.

The differing degrees of shading and stippling shown in FIGS. 1–9 represent a contrasting appearance.
